LUBRICATING PADS FOR RAILWAY CAR JOURNALS

Robert S. Brooks and Frederick L. Berridge, Montreal, Quebec, Canada, assignors to Joseph Robb & Co., Limited, Montreal, Quebec, Canada

Filed Feb. 29, 1960, Ser. No. 11,650

4 Claims. (Cl. 308—243)

This invention relates to journal lubricators of the type comprising a resilient pad or packing to ensure positive supply of lubricating oil to the journals of railway vehicles or the like.

In the conventional railway vehicles the journal extends into a journal box having an oil reservoir packed with waste. Lubricating oil is poured into the bottom of the journal box which acts as a reservoir, the oil being supplied to the journal by capillary action in the waste. After a period of operation the waste sets in the bottom of the journal box, out of contact with the journal, so that the journal is no longer lubricated. Continued movement of the car under such conditions results in great friction and heat, and causes hot boxes.

More recently the waste packing of journal boxes of railway cars has been replaced by a resilient oil retaining pad which to a certain extent overcomes the above mentioned disadvantages. It is the object of the present invention to provide an improved pad which ensures without fail permanent lubrication of the journal.

The pad in accordance with the invention consists essentially of an outer tubular core of generally elliptical cross-section, arranged with its axis transverse to the axis of the journal; an endless elliptical spring is contained in the outer core and extends longitudinally of the journal; also contained in the outer core, and encircled by the spring, is an inner core. The three elements mentioned above, namely the outer and inner cores and the spring are preferably used in combination, but it is considered to be within the scope of the invention to use a combination of any two of them; thus the outer core and spring may be used without the inner core, the outer and inner cores without the spring, and the inner core and spring without the outer core.

Whichever of the four combinations mentioned above is used, the whole is contained in an outer covering of oil permeable, wear resistant fabric, comprising pulls for removing the pad. Two or three individual pad sections connected together lengthwise are preferably used according to the invention, but single pads or combinations of four or more are not excluded.

Two embodiments of the invention are illustrated by way of example in the accompanying drawings, in which:

FIG. 1 is a cross-section of a conventional journal box containing a pad according to a first embodiment of the invention, made in three sections, the view being taken on line 1—1 of FIG. 2;

FIG. 2 is a longitudinal section taken on line 2—2 of FIG. 1;

FIG. 3 is a cross-section of an identical journal box, taken on line 3—3 of FIG. 2, but containing a pad according to a second embodiment of the invention, made in two sections;

FIG. 4 is an exploded perspective view of the cores and spring.

Referring to the drawings, numeral 10 represents a conventional journal box having side walls 11 and a generally concave bottom wall 12. Projecting into the journal box through an opening 13 in the rear thereof is a journal 14 having an end flange 15. The journal is adapted to support a railway car by means of conven-

2

tional journal bearings (not shown) riding on the upper surface of the journal.

The pad according to the invention comprises an outer chenille covering 16 of quality cotton tufted on a strong canvas backing washed and preshrunk to size. The covering should be wear and glaze resistant and oil permeable. If two or more pad sections are provided, as shown in the drawings, the covering may consist of a continuous wide strip of rectangular shape looped and stitched together to form the several sections.

As shown in FIG. 1, strong wick pulls 17 are sewn to the covering 16 to permit easy removal of the pad. Brass grommets may be used instead of the pulls 17.

In accordance with the invention it is preferable to provide two or three pad sections as shown respectively in FIGS. 3 and 1. The internal structure of each pad section is the same in either case, except that if two sections are provided they are of the same size, whereas if there are three sections, the central one is somewhat larger than the two side sections, in order to suit present journal box designs.

Each section of the covering 16 contains an outer tubular elliptical core 18 arranged with its axis transverse to the axis of the journal 14 and to the axis of the looped section of covering 16; the ends of the sections are partly closed by canvas strips 19 to retain the core 18, the strips leaving however, open spaces on either side to allow easy access of the oil to the core 18.

An endless elliptical flat spring 20 is contained within each outer core 18 and extends longitudinally of the journal 14, namely, with its axis transverse to the journal. Also contained in the outer core 18, and encircled by the spring 20, is an inner core 21. The spring 20 has preferably a fabric facing 22 externally thereon to prevent its cutting the outer core 18.

The outer and inner cores 18 and 21 are of the same material, namely a resilient, oil retaining sponge, preferably of polyurethane foam.

The combination of outer and inner cores and spring 20 in accordance with the invention provides particular advantages. The two cores give a maximum of oil retention, and the inner core and the spring cooperate to expand the outer core and to keep the covering in contact with the journal under a slight pressure. The oil passes through the covering and is continuously supplied to the journal ensuring constant lubrication.

The pad is furthermore reversible, which doubles its useful life, and flexible for easy installation and removal.

As mentioned previously, it is considered to be within the scope of the invention to omit any single one of the elements contained within the covering. Such simplified structure still offers a large part of the advantages of the invention. Thus the inner core 21 may be left out; oil retention is then somewhat less, and to obtain the same pressure of the covering on the journal the spring has to be more rigid. If on the other hand the spring is omitted, the pad has to be compressed to a greater extent if the pressure is to be the same. It is also possible to omit the outer core; in this case the spring acts directly on the chenille covering together with the inner core.

It is understood that in all cases the pressure of the pad on the journal can be suitably adjusted by calibrating the spring and by providing core combinations of thickness properly proportioned to the dimensions of the journal box.

The invention is limited not to the above described embodiments, but only by the scope of the appended claims.

What we claim is:

1. A lubricator for railway journals having an axle, an axle bearing and a journal box providing an oil well,

a multi-lobe lubricating pad located in said journal box and conforming to the surface of the lower half of said axle and to the adjacent wall of the journal box, the said lubricating pad comprising an outer fabric covering tufted on its outer surface, the said covering being stitched to form a series of separate tubular compartments whose axes are disposed parallel to the axis of said axle, an outer tubular core of oil retaining, resilient material in each of said separate tubular compartments, the axis of said outer tubular cores being transverse to the axes of the said separate tubular compartments, an elliptical shaped spring member within each of said outer tubular cores, the said spring members having their axes parallel with the axes of said outer tubular cores, and an inner core of oil retaining, resilient material within each of said outer cores and springs.

2. A lubricator for railway journals as set forth in claim 1, in which the said elliptical springs are of relatively narrow width and are embedded on all surfaces between the said outer and inner cores.

3. A lubricator for railway journals as set forth in

claim 1 in which the said elliptical springs have their outer surface covered by a fabric facing for friction engagement with the adjacent surfaces of the said outer cores.

5. A lubricator for railway journals as set forth in claim 1, in which the open ends of the said separate tubular compartments are partly closed off by core retaining resilient members.
